CORPORATION OF OHIO

PAPER-FEEDING MECHANISM

Application filed December 6, 1927. Serial No. 238,100.

This invention relates to mechanism for feeding a continuous web of paper to a printing machine wherein a continuously rotating printing drum is associated with 5 an intermittent paper feed. One of the main objects of the invention is to enable accuracy in the feeding of such paper.

A feature of our invention is the provision of means for feeding a continuous web 10 of paper in such manner that it will be accurately presented for successive imprints though different grades or different weights of paper may be employed. In effecting this, we find it important to have paper feed 15 mechanism act simultaneously on a comparatively large area of the web, and we effect this by directing the web about a portion of the periphery of the feed drum against which the web is pressed by suitable tapes 20 tensioned about such portion of the drum.

Our paper feed mechanism is especially well adapted for cooperation with a printing machine, known as the multigraph, 25 wherein a rotary printing device is provided carrying suitable cameo characters, as for instance, individual type or embossed strips.

Our invention includes various features 30 illustrated in the drawings and contributing to the general operation, all of which will be hereinafter more fully explained in connection with such drawings.

In the drawings, Fig. 1 is a side elevation of our complete apparatus including the 35 paper feed per se, a multigraph machine and rewinding mechanism; Figs. 2 and 3 are vertical longitudinal sections of the apparatus shown in Fig. 1 in planes parallel with Fig. 1, the location of these planes being indicated by lines 2-2 and 3-3 on Fig. 4; Fig. 4 is a vertical transverse section through the axis of the feed drum, as indicated by the line 4-4 on Fig. 1; Fig. 5 is a detail of the mechanism for disconnecting 40 the gear between the multigraph and paper feed; Fig. 6 is a detail illustrating the reusable drive for the feed drum.

In Figs. 1, 2 and 3, we have illustrated a 45 usual multigraph printing machine comprising the following members, namely; end

frame plates 10 and 11 projecting upwardly from a base 12, and journaled in these end plates, a shaft 14 on which are mounted rings 15 and 16, resting on which is a segment 17 shown as secured to the shaft 14 by 55 spring hooks 18. The segment carries suitable printing form which is illustrated conventionally at 20. This printing form may be a blanket carrying embossed strips, as shown in Patent No. 1,438,580, of our as- 60 signee, The American Multigraph Company, or the segment may be provided with rails carrying individual type, as is frequent in the multigraph. Suitable means is provided for inking the multigraph form, for instance, ribbon spools, as at 25 and 26, mounted in the segment drum and carrying a ribbon 27 overlying the form.

Mounted in the frame members of the multigraph, parallel with the drum shaft, 70 is a platen shaft 30. On this shaft is rotatably mounted a rubber faced platen roller 31 adapted to coact with the form. This platen roller is connected by a gear 33 to a gear 34 on the drum. 75

In the present machine we combine such mechanism as just described with a paper feed drum geared with the multigraph to feed the paper periodically between the multigraph drum and platen, and we may also 80 provide mechanism for automatically rerolling the printed web.

The frame of the paper feed mechanism per se comprises a pair of upright plates 40 and 41 secured to a suitable base 42. Journaled in these upright plates is a shaft 44. Rigidly mounted on this shaft is a drum 45 having a smooth cylindrical periphery. Co-acting with this drum for about half its circumference are several endless belts 50, 85 90 three being shown. These belts loop over a roller 51 above the drum 45 and a roller 52 below it, each of these rollers being beyond the central vertical plane of the drum. The outer reaches of the belts also pass over a 95 guide roller 53, journaled in the frame plates and over a tension roller 54, carried by a pair of levers 55 pivoted to the respective frame plates. Tension springs 56, acting on these levers tend to swing the roller 100

54 away from the drum 45, and thus tension the belts, maintaining the inner reach tight against the drum for about half its periphery. The belts are driven in correspondence with the peripheral movement of the drum 5 by a gear 57 on the drum operating idlers 58 to a gear 59 on the roller 52.

The web of paper is fed into the grip of the belts and the drum 45 beneath the roller 10 51 and thence passes around the front half of the drum 45, and then over the roller 52 to the multigraph. Such web of paper is shown at A in Figs. 1 and 3.

The paper is supplied to the machine in 15 the form of a roll A¹, Fig. 1, and this roll is suitably mounted, as for instance, by having an axial rod 60 resting in recesses in brackets 61 suitably carried. A brake is provided in the form of a comparatively 20 heavy plate 63 adjustably carried on rods 64 pivotally supported at one end, the weight resting by gravity against the surface of the roll. From the roll the web passes upwardly over a guide roller 76, thence to a guide roller 89, and thence toward the front beneath the belt roller 51, and between the belts and the drum 45, leaving the underside of the drum. The web A passes from the drum on top of the belts until it leaves the feed 25 mechanism per se, and enters the multigraph machine passing between the multigraph drum and its platen, where it is printed as desired.

The multigraph drum in this apparatus 30 is continuously rotated, but the printing form occupies only a fraction of the total periphery of the drum, and accordingly as the paper passes directly from the paper feed drum to the multigraph, the paper feed 35 drum must have the same peripheral speed of the multigraph drum, but must operate intermittently. To effect this, we provide a ratchet mechanism, best illustrated in Figs. 2, 4 and 6, and which will now be described.

40 As is shown, we have mounted freely on the shaft 44 of the paper feed drum the hub 90 of a gear 91, this gear normally meshing with an idler 92 which meshes with the multigraph gear 34 mentioned. The loose gear 91 has pivoted to it a pawl 93 (Figs. 2 and 6) which is adapted to coat with a ratchet wheel 95 which is rigidly connected with the feed drum 45. We have shown the ratchet wheel rigidly mounted on a sleeve hub 96 which extends through the frame 45 plate 40 and is pinned at 97 to the shaft 44, the drum 45 being also pinned to this shaft. It results that the rotation of the multigraph drum may deliver a corresponding rotation 50 to the drum 45 (the gears 34 and 91 being of the same diameter) so long as the pawl 93 engages the ratchet 95.

The period of engagement of the pawl 93 with the ratchet 95 is determined by a compound cam 100, 101 on which rides a roller

97 carried by the pawl, this roller being pressed against the periphery of the cam by a spring 98 secured to the gear at 99. The cam is of an adjustable extent and preferably comprises two rings side by side. As 70 illustrated in Fig. 4, one of these rings, designated 100, may be secured as shown to the frame member 40, and the other ring 102 may be loose upon a clamping ring 105, which may be supported by screws 106 75 mounted in the frame plate. These screws will thus serve to draw the plate 101 tightly against the plate 100, so that they act as a unitary stationary cam, but by loosening these screws the ring 101 may be shifted circumferentially, and thus vary the arcuate 80 length of the cam region. Both the rings have a concentric periphery for a considerable portion of their extent.

The cam region is adjusted in extent with 85 reference to the arcuate length of the form 20 on the multigraph drum. The concentric portion of the compound cam maintains the driving pawl 93 idle, but the cam region allows that pawl to come into engagement 90 with the ratchet teeth, under the influence of the spring 98, for an angular distance at least as great as that of the form 20, so that paper is fed sufficiently for the form to print. The length of the non-concentric 95 region of the cam determines the duration of the feed of the paper.

To prevent displacement of the web, or overfeeding by momentum, we employ the following mechanism. On the shaft 44 of 100 the feed drum, outside of the plate 40, is a brake band 111, the end portions of which have blocks 112 and 113 mounted on them. A rod 114 pivoted to one of these blocks extends loosely through the other and beyond 105 the block is surrounded by a compression spring 115 adjustably compressed by nuts 116.

About the mid region of the brake band 111 there is secured to it a block 117 which 110 is pinned to the frame plate 40. The spring 115 is so adjusted that the friction on the brake drum will lock the brake to the drum against displacement when there is no power on the drum, but the friction is not sufficient 115 to interfere with the normal power driving the drum independently. Accordingly power on the drum will rotate it but when the power is taken away the drum will come to an immediate stop.

The multigraph is frequently mounted on the top of a plate carrying power transmitting gearing, which plate is mounted on top of a suitable stand. Our paper feed mechanism may readily have its frame and other parts connected to such multigraph support. Thus, as shown in Figs. 1, 2 and 3, the multigraph frame rests on a plate 140 which rests on top of a usual tubular stand 141. We may arrange the base plate 42 of the 125 130

paper feed with a horizontal flange 142 (Fig. 3) and a vertical flange 143 engaging the top and vertical wall of the multigraph transmission frame 140. Suitable screws as 5 145 may lock the paper feed frame to the multigraph transmission plate. At its opposite edge the paper feed frame may be readily supported by upright standards 147. The rod 64 carrying the braking weight 63 10 may readily be a rock arm on a shaft 65 journalled in brackets 148 clamped to standards of the multigraph frame 141. The paper roll supports 61 may be clamped to the standards 147 of the paper feed. 15 The construction just described is simple and inexpensive and has the advantage of intimately connecting the paper feed frame with the multigraph support and at the same time does not interfere with the multigraph being lifted off of its support, whenever desired, without disturbing the paper feed.

We have shown the multigraph as driven by gearing carried by the plate 140 which 25 rests on the multigraph stand. As shown in Fig. 1, this plate has suitable bearings in which is journalled a shaft 150 carrying a driving pulley 151. A belt 152 is shown as running onto this pulley from a suitable 30 motor 153. At the end of the shaft 150 is a gear 155 (Figs. 1 and 2) which may mesh with the gear 33 of the platen, which in turn meshes with the gear 34 of the multigraph drum. As this gear 34 is connected through 35 the idler 92 with the paper feed, it will be seen that the motor 153 supplies the power for both the multigraph and the paper feed. This same power may operate the take-off roll, if one is employed.

40 As shown, the printed web passes from the bite of the platen roll and printing segment of the multigraph over a roller 160, suitably journalled in the end frame plates 10 and 11, thence downward to the spool 165 when it is wound. The spool 165 is 45 journalled in brackets 166 mounted on the tubular stand 141. The shaft 150 carries a pulley 170 which drives a pulley 171 by means of a suitable belt 172. The pulley 50 172 is mounted on the spool 165 and drives the spool through a slip clutch, not shown.

To enable the paper feed mechanism to be disconnected from the multigraph in a very simple manner, we make the idler 92, normally connecting them, shiftable on its supporting rod 200. We may effect this by a 55 push button 201 (Fig. 5) on the end of a rod 202 carrying a shipper fork 203, occupying a groove in the idler 92. The spring 205 normally maintains the idler in an engaged position but allows it to be moved inwardly out of engagement whenever desired.

60 It will be understood from the description above given of the embodiment shown in the drawings, that we have provided a compara-

tively simple adjunct for the multigraph which will result in feeding a continuous web of paper to it, in amounts corresponding to the extent of the form of the multigraph drum. The printed web may be disposed of 70 by shearing off sections of the web corresponding to the amount to be printed, or fan-folding it if desired, but we have shown it being wound on a spool.

We claim:

1. The combination, with a multigraph comprising a rotary drum and an impression platen, of a paper feed drum arranged to move at the same speed as the multigraph drum, a gear mounted coaxially with said paper feed drum and constantly geared with the multigraph, and settable means for automatically connecting and disconnecting said gear to the paper feed drum during a portion of one rotation of the multigraph drum. 85

2. The combination with a rotary printing couple, one member of which is adapted to carry a segmental printing form, a paper feed drum, a driver for said drum geared with the rotary couple, a toothed wheel on the paper feed drum, a pawl carried by the driver and adapted to engage said toothed wheel, and a cam for controlling the time the pawl is in engagement. 90

3. The combination with a printing couple, of a paper feed therefor comprising a rotary drum, a rotary driver therefor, a toothed wheel on the drum, a pawl carried by the driver and adapted to coact with the drum, and an adjustable cam causing the 100 connection and disconnection between the pawl and toothed wheel. 105

4. The combination with a rotary printing couple of a paper feed drum, a set of endless tapes embracing the same, means for guiding a continuous web of paper from a roll thereof into position between the tapes and drum and thence to the printing couple, a toothed wheel rigid with the drum, a driving device, a pawl carried thereby to engage the toothed wheel, and an adjustable device for controlling the pawl. 110

5. The combination with a printing couple of a paper feed drum, a set of endless tapes embracing the same, means for guiding a continuous web of paper from a roll thereof into position between the tapes and drum and thence to the printing couple, a toothed wheel at one end of the drum and rigid therewith, a rotary driving device coaxial of the drum, a pawl carried thereby to engage the toothed wheel, and a cam of adjustable length for controlling the period of engagement of the pawl and toothed wheel. 115

6. The combination of a rotary printing couple, of a paper feed drum with its axis parallel with the axis of the couple, a ratchet wheel rigid therewith, a concentrically mounted rotary driver at the end of the drum, a pawl carried thereby and adapted to 125 130

coact with the ratchet wheel, a cam of adjustable length for controlling the time of coaction of the pawl, endless tapes embracing the drum, means for supporting a roll of paper and means for guiding the web thereof upwardly and then laterally over the tapes and drum and thence downwardly and backwardly between the tapes and drum and thence to the printing couple, and means for applying tension to the web.

7. The combination with a rotary printing couple of means for feeding paper thereto comprising the following cooperating instrumentalities, namely a paper feed drum, a driving gear therefor rotatable independently thereof, a toothed wheel on the paper feed drum, a pawl on the driving gear, an adjustable cam adapted to cause the movement of the pawl into and out of coaction with the toothed wheel on each rotation of the driving gear, and a friction brake constantly acting on the feed drum.

8. The combination of a rotary printing drum adapted to carry a segmental printing form, a rotary underrunning platen, geared thereto, a paper feed drum of the same diameter as the printing drum and mounted on a parallel axis, a driving gear concentric with the paper feed drum located at one end thereof and connected by an idler with a gear on the printing drum, a ratchet wheel on the paper feed drum, a pawl on the driving gear, and an adjustable cam adapted to cause the movement of the pawl into and out of coaction with the ratchet on each rotation of the driving gear.

9. The combination of a rotary printing drum adapted to carry a segmental printing form, a rotary platen geared thereto, a paper feed drum mounted on a parallel axis, a driving gear for the paper feed drum geared with the printing drum and platen, a ratchet wheel on the paper feed drum, a pawl on the driving gear, an adjustable cam adapted to cause the movement of the pawl into and out of coaction with the ratchet on each rotation of the driving gear, and a brake acting frictionally on the feed drum.

10. The combination of a rotary printing drum adapted to carry a segmental printing form, a rotary platen geared thereto, a paper feed drum, a rotary member for driving the paper feed drum geared with the printing drum and platen, a releasable connection between said member and the paper feed drum, means adapted to cause such release, a set of endless belts embracing the paper feed drum, and means for guiding a continuous web of paper between the belts and paper feed drum and thence between the printing drum and platen.

11. The combination with a rotary printing drum having a segmental form extending materially less than the periphery of the drum, a roller platen coacting with the

drum, a feed drum constantly engaging a continuous web of paper for feeding it to the pass of the printing drum and platen, a gear concentric of the feed drum and constantly geared with the printing drum, and means for periodically establishing and interrupting connection between said concentric gear and the paper feed drum while the printing drum rotates continuously.

In testimony whereof, we hereunto affix our signatures.

PETER M. COLQUHOUN.
